(57) **CLAIM**

The ornamental design for a shoe upper with shoelace, as shown and described.

DESCRIPTION

The sole FIGURE is a top view of a shoe upper with shoelace showing our new design.

The broken lines immediately adjacent the shaded areas represent the bounds of the claimed design while all other broken lines are directed to environment and are for illustrative purposes only; the broken lines form no part of the claimed design.

1 Claim, 1 Drawing Sheet
